END STOP FOR SLIDE ACTUATED
FASTENERS

Robert C. Legat, New Britain, Conn., assignor to
G. E. Prentice Manufacturing Company, New
Britain, Conn., a corporation of Connecticut

Application June 2, 1933, Serial No. 674,031

19 Claims. (Cl. 24—205)

This invention pertains to slide-actuated fasteners of the kind in which series of complementary interlocking elements are arranged along the opposite edges of a gap or opening in a garment, receptacle or other article of flexible material, and relates more particularly to a separable bottom stop for such a fastener adapted to permit complete separation of the opposite edges of the gap or opening. In my Patent No. 1,893,823, dated January 10, 1933 I have disclosed and claimed one very desirable form of separable bottom stop for fasteners of this class wherein each of the complementary interlocking stop members is of one piece unitary construction and made preferably by bending a sheet metal blank. These one piece stop members of my said patent are desirable, not only from the standpoint of economy and ease of manufacture, but also by reason of their permissive small dimensions, while at the same time providing secure anchorage to the stringers and affording the desired slider limiting function. However, in practice, I have found that in the hands of unskilled or unthinking persons these end stops are sometimes subjected to such abnormal stresses, for example, in the endeavor to separate the lower ends of the stringers by direct pull without proper preliminary actuation of the slider, that the socket member of the stop is sprung apart or otherwise permanently distorted so that its normal function is destroyed. With the object of overcoming this difficulty, I have further improved the stop device of my prior patent so as effectively to prevent such springing of the walls of the socket member. In accomplishing this result I preferably provide the lower end of the pin member of the stop with a tooth adapted to enter an opening or recess in the bottom wall of the socket member of the stop, such tooth, when seated in this opening or recess, positively opposing lateral stress tending to pull the pin member sidewise out from between the front and rear walls of the socket. As a further safeguard, I may also extend the bottom wall of the socket upwardly and rearwardly so as to overlap the rear wall of the socket, and thus produce a clamp or reinforce element which assists in preventing the walls of the socket from being spread or sprung apart.

Experience with the use of my separable stop, as proven in my patent above referred to, has disclosed to me that the entry of the pin through the channel of the slider and downwardly into interlocking engagement with the socket member of the stop is facilitated if the pin, or at least the

lower portion thereof, be longitudinally curved. It may be noted that the channel in the slider is not straight and thus if a pin member of substantial length be employed (which is desirable in order to obtain the proper anchorage to the stringer without undesirably widening the pin member) it is sometimes cramped in passing it through the slider channel. Thus, in accordance with the present invention I curve the pin to some extent, as above stated, and find that it enters the slider channel very easily and may be pushed down to its furthest limit where it properly seats in the socket without undue effort.

In the accompanying drawings I have illustrated certain desirable embodiments of the invention by way of example, and in the drawings have shown my improved separable end stop as made from sheet material. However, it is to be understood that in its broader aspects the invention is not limited to the type of material employed or to the exact mode of procedure in making and applying the end stop but that all desirable changes in shape, form, material and arrangement of parts, and the substitution of equivalents are to be considered as falling within the purview of the invention as expressed in the claims appended hereto.

In the drawings:

Fig. 1 is a fragmentary front elevation illustrating the lower portion of a slide-actuated fastener having my improved end stop applied thereto;

Fig. 2 is a plan view of a blank useful in forming the socket member of the stop shown in Fig. 1;

Fig. 3 is a front elevation to larger scale of the socket member made from the blank of Fig. 2;

Fig. 4 is a rear elevation of the same socket member;

Fig. 5 is an edge elevation of said socket member;

Fig. 6 is a top plan view of the socket member before application to the stringer;

Fig. 7 is a front elevation of a blank useful in making the pin member of the stop of Fig. 1;

Fig. 8 is a rear elevation of the pin member made from the blank of Fig. 7;

Fig. 9 is a section on the line 9—9 of Fig. 8;

Fig. 10 is a top plan view of the pin member before application to the stringer;

Fig. 11 is a vertical section substantially on the line 11—11 of Fig. 6, showing the socket member with the pin member associated therewith and indicating the position of the parts relative to the fastener elements and the slider;

50
55

Fig. 11^a is a fragmentary section through the edge portion of a garment, showing a stringer and end stop secured thereto, and indicating a novel way of anchoring the garment to the end stop;

5 Fig. 12 is a front elevation of a blank useful in making a socket member of modified construction;

Fig. 13 is a plan view of the socket member made from the blank of Fig. 12;

10 Fig. 14 is a plan view of a blank useful in making a modified form of pin member;

Fig. 15 is a front elevation of the pin member made from the blank of Fig. 14 and shown assembled on the stringer;

15 Fig. 16 is a vertical section showing the socket member of Fig. 13 assembled with the pin member of Fig. 15; and

Fig. 17 is a front elevation illustrating the 20 operation of entering the pin of Fig. 15 through the slider channel for engagement with the socket member of Fig. 13.

Referring to Fig. 1, the numerals 1 and 2 designate flexible stringers such as are commonly employed for supporting the opposed series of 25 fastener elements in a fastener of the type under consideration, such stringers, as shown, carrying the series of fastener elements 3 and 4 respectively. The fastener elements of the opposed series are moved into and out of engagement by 30 means of a slider 5 which may be of any approved construction. As illustrated, special guide elements 3^a and 4^a, such as disclosed in the patent to Prentice, No. 1,899,479, are disposed at the lower ends of the series of fastener elements 35 3 and 4 respectively. My improved bottom stop is applied to the lower ends of the stringers 1 and 2 and comprises the socket member 6 and the cooperating pin member 7. Referring to Figs. 2 to 6 inclusive, the socket member preferably 40 consists of a unitary piece of sheet metal comprising the elongate portions 8 and 9 integrally joined to the central portion 10, the latter having the upwardly extending part 10^a. Preferably the outer extremities of the parts 8 and 9 are curved, as shown at 12 and 13, respectively, and these 45 curved end portions are integrally united by neck members 14 and 15, respectively, to curved end portions of outer members 16 and 17, respectively. The member 16 is preferably furnished with a notch 22 in its upper edge and with a tongue 23 projecting from its lower edge. This 50 tongue is furnished with an opening or recess 24. Preferably the upwardly extending part 10^a is provided with laterally projecting tabs 25 and 55 26 at its opposite edges. The outer end portions of the parts 8 and 9 and the adjacent portions of the parts 16 and 17 are furnished with openings 27 for a purpose to be described.

The blank as thus formed is now subjected to 60 bending operations, for example, by means of suitable dies or otherwise, whereby the parts 8 and 9 are brought into substantially parallel relation, being integrally united by a fold of the material at 10, and the material is bent at the neck 65 portions 14 and 15 so as to cause the parts 16 and 17 to overlie the parts 8 and 9 thereby forming two-ply jaws defining between them the pocket 11 (Fig. 6) which is adapted to receive the beaded edge portion of the stringer 1. The 70 end portions of the parts 16 and 17 are disposed in substantially parallel spaced relation, forming the front and rear portions of the wall of the socket 18, the latter being open at its upper end, and their free edges are turned inwardly to 75 form the flanges 19 and 20 (Fig. 6) leaving a slot

21 between them for the passage of a narrow neck portion of the pin member hereafter described. The tongue 23 is bent at substantially right angles to the vertical plane of the part 16 so as to form a substantially horizontal bottom closure for the socket 18 defined by the parts 18, 16, 17, and the flanges 19 and 20, such socket being shaped to receive the pin member by downward endwise movement of the latter. As indicated in Fig. 6, the opening 24 in the tongue 10 23 is disposed in the bottom closure of this socket 18. Preferably the tongue 23 is made long enough so that its extremity 23^a may be bent upwardly (Figs. 4 and 5) as to overlie the rear wall 17 of the socket member, thus constituting a clamping 15 or retaining member adapted to resist spreading or springing of the walls 16 and 17 away from each other. The parts 25 and 26 are folded back to reinforce fold 10 at its upper portion.

Referring to Figs. 7 to 10 inclusive, the pin 20 member preferably comprises a piece of sheet metal 30 having laterally extending arms 31 and 32, said arms preferably having curved extremities and being provided with openings 34. The upper part of the center of this blank is desirably 25 furnished with a recess or slot 37, and this central part of the blank is also provided with a downwardly directed tongue or tab 35.

Having provided this blank, it is then bent, as shown more particularly in Fig. 10, so that the 30 central part 30 forms a more or less cylindrical, tubular, elongate pin or head while the wings 31 and 32 are disposed in substantially parallel relation, preferably being brought closer together immediately adjacent to the pin so as to form a 35 relatively narrow neck portion 30^a. The space within the tubular pin merges with the space between the parts 31 and 32 to form a pocket for the reception of the beaded edge of the stringer. The pin is of such size as to fit within the socket 40 18 of the socket member, with the lower end of the pin seating on the bottom closure 23 of the socket, the narrow neck portion of the pin sliding in the slot 21 between the flanges 19 and 20 of the socket member as the pin is advanced 45 downwardly endwise into the open topped socket. The downwardly projecting tongue 35 is bent or curled, as indicated in Fig. 9, so as to form a substantially solid tooth projecting downwardly below the lower edges of the parts 31 and 32. 50 Preferably, as shown in Fig. 8, this tooth is curved away from the outer edge 38 of the part 30.

Having provided the socket member 6 and the pin member 7 as described, these members are secured to the respective stringers 1 and 2 by inserting the edges of the stringers in the sockets 11 and 36 respectively, and then pressing the jaws of the socket member, and the edge portions of the part 30 of the pin member into firm engagement with the material of the stringers. Rivets 60 27^a and 34^a are now passed through the openings 27 and 34 of the sockets and pin members, respectively, and through the stringer fabric, and these rivets are then headed over to secure the parts in position. If desired, in order to anchor 65 the metal to the fabric more firmly, the walls of the socket and pin members may be struck inwardly or indented as indicated at 39 in Fig. 1. Furthermore, to secure a very firm anchorage of the end stop structure, especially when the garment material M (Fig. 11^a) is stiff or heavy, for example leather, a secondary, but smaller, rivet 34^b may be passed through the rivet 34^a and headed over against the garment material, a similar rivet being associated with the rivet 27^a. 75

In the operation of this separable stop member, and assuming that it is desired to assemble the parts preparatory to the closing of the gap, the slider is brought down into the position indicated

5 in broken lines in Fig. 11, so that its lower end rests, for example, on the upper edges of the jaws of the socket 11. The pin member of the stringer 2 is now passed down through the channel in the right-hand side of the slider, as viewed in Fig. 11, 10 and is caused to move downwardly into the socket 18 until the tooth 35 projects through the opening 24 in the bottom wall 23 of the socket. The parts are now properly assembled and the slider may be actuated in usual manner to bring the opposed series of fastener elements into engagement. 15 When the stop members are thus associated, the engagement of the tooth 35 with the opening 24 provides a positive anchorage such that direct lateral stress applied to the lower portions of the 20 stringers can not pull the pin member from between the flanges 19 and 20 of the socket 18 by springing the latter apart, and thus the stringers can not be improperly separated at a point below the slider as is sometimes accomplished by the 25 application of severe pull applied to the lower portions of the stringers. Obviously the arrangement of the clamping member 23a overlapping the rear wall of the socket further assists in preventing separation of the flanges 19 and 20.

30 Referring to Figs. 12 and 13, a slightly modified form of socket member is shown, such socket member being substantially like that shown in my prior patent above referred to but with provision for reception of a retaining tooth on the pin member. This socket is preferably made from a blank comprising a central part 42 and lateral wings 40 and 41, the central part having a notch 43 at its upper end while the part 41 has a downwardly projecting tab 44 provided with an opening or recess 45. This blank is so bent as to provide two 35 ply jaws (Fig. 13) defining between them the socket 46 for the reception of the edge of the stringer, and also jaw members defining between them the socket 47 for the reception of the pin member of the stop. The tab 44 is turned inwardly so as to form a bottom wall for the socket 47, such wall having the opening 45 therethrough. The free edges of the jaws which form the socket 47 are turned inwardly to provide the retaining flanges 48 and 49.

50 The pin member is conveniently made from a blank such as shown in Fig. 14 comprising a central part 50 and lateral portions 51 and 52, the central part having a downwardly projecting tab 53. This blank is bent to provide a socket adapted to receive the beaded edge of the stringer 2 and the downwardly projecting tab 53 is preferably bent or folded so as to form a tooth which may be of the construction illustrated in Fig. 9, for example. However, if the metal be of sufficient thickness, this tab need not be folded but may be left flat substantially as shown in Fig. 15. Preferably the pin member thus formed is longitudinally curved so that the exposed or outer surface 54 of this pin member is curved from end to end.

55 The socket member and the pin member thus provided are secured to edges of their respective stringers by pressure or otherwise so as to anchor them firmly in position, and these parts may be indented as shown at 55 so as to anchor them securely in place.

In Fig. 16 I have illustrated the arrangement of the socket member of Fig. 13 and the pin member of Fig. 15 when assembled in position for operative engagement. It may be noted that the

curved shape of the pin member facilitates its passage downwardly through the slider channel (Fig. 17) and that the tooth member 53, when the parts are assembled, passes down through the opening 45 in the bottom wall 44 of the socket member, thus positively anchoring the parts together and thereby preventing them from being pulled apart laterally by improperly applied and abnormal stress.

When herein I have employed the terms "top", "bottom", "horizontal", "vertical", etc., I have done so for convenience in description and with reference to the disposal of the parts as illustrated in the drawings, but without intent thereby to imply that the improved structure may not be differently disposed when in use.

I claim:

1. A separable end stop for slide actuated fasteners, said stop comprising a socket member and a pin member, the socket member having an elongate socket provided with a bottom closure and with an elongate slot in its wall, the pin member having a pin adapted to fit within the socket, the pin member and the bottom closure of the socket having complementary interfitting parts which engage each other when the pin is seated in the socket and which thereby act to oppose stress tending to pull the pin laterally out through the slot in the socket wall.

2. A separable end stop for slide actuated fasteners, said stop comprising a socket member and a pin member, the socket member consisting of a unitary piece of sheet metal bent to form an elongate socket provided with a bottom closure and having an elongate slot in its wall, said bottom closure having an aperture therein, the pin member having a head portion adapted to fit within the socket and to seat on the bottom closure of the latter, the pin also having a narrow neck portion adapted to slide in the slot in the wall of the socket member, the pin having a tooth at its lower end adapted to project into the aperture in the bottom closure of the socket.

3. A separable end stop for slide actuated fasteners of the kind in which opposed series of fastener elements are carried by flexible stringers and are moved into and out of engagement by a slider, said stop comprising a socket member and a pin member, the socket member having an elongate socket closed at its bottom and having a longitudinally extending slot in its wall, the bottom closure of the socket having an opening therein, the pin member consisting of a unitary piece of sheet metal bent to provide a head portion adapted to fit within the socket and to seat on the bottom closure of the latter, the pin member having a portion adapted to slide in the slot in the socket member, and a tooth projecting from the lower end of the head portion of the pin for engagement with the opening in the bottom closure of the socket.

4. A separable end stop for slide actuated fasteners of the kind in which opposed series of fastener elements are carried by flexible stringers and are moved into and out of engagement by a slider, said stop comprising a socket member and a pin member, the socket member having side walls terminating in opposed flanges spaced to leave an elongate slot between them, said walls defining a socket, and means providing a bottom closure for the socket, the pin member comprising a pin adapted to fit within the socket, the pin having a tooth projecting downwardly from its lower end, the bottom closure of the socket having an element engageable by the tooth when

- the pin member is seated in the socket, thereby to oppose stress tending to pull the pin laterally out through the slot between the flanges of the socket wall.
5. A separable bottom stop for a fastener of the kind having a pair of stringers carrying opposed series of interengageable fastener elements, and a slider for moving the opposed series of elements into and out of operative engagement, said stop comprising independent separable members each secured to one of the stringers, respectively, adjacent to the lower end of the corresponding series of fastener elements, one of said stop members being a socket member and the other a pin member, each of said members consisting of a single unitary piece of sheet material, the socket member having a socket provided with spaced walls having free edge portions spaced from each other, the socket member also having an apertured bottom closure for the socket, said closure being integrally joined to one wall of the socket and having a tongue projecting upwardly substantially parallel to the outer surface of the other wall of the socket, and the pin member having a part shaped to fit within the socket of the socket member and to seat on the bottom of the latter, the pin having a tooth which projects into the opening in the bottom of the socket when the pin is seated in the latter.
10. A separable end stop for slide actuated fasteners of the kind in which opposed series of fastener elements are carried by flexible stringers and are moved into and out of engagement by a slider, said stop comprising a socket member and a pin member, the socket member having walls terminating in opposed edges spaced to leave an elongate vertically extending slot between them, said walls defining a socket, and a bottom closure for the socket, said bottom closure being provided with a tongue portion substantially perpendicular to the plane of the bottom closure proper and united to one edge of the latter, said tongue extending upwardly in substantially parallel relation to the outer surface of one wall of the socket member.
15. A separable end stop for slide actuated fasteners of the kind in which opposed series of fastener elements are carried by flexible stringers and are moved into and out of engagement by a slider, said stop comprising a socket member and a pin member, the socket member having walls terminating in opposed edges spaced to leave an elongate vertically extending slot between them, said walls defining a socket, and a bottom closure for the socket, said bottom closure being integrally united to the socket wall at one side of the slot and overlapping the outer surface of the socket wall at the opposite side of the slot, thereby so connecting said walls as to prevent separation of the flanges.
20. A separable end stop for slide actuated fasteners of the kind in which opposed series of fastener elements are carried by flexible stringers and are moved into and out of engagement by a slider, said stop comprising a socket member and a pin member, the socket member consisting of a single piece of sheet metal bent to provide walls arranged to define a vertically elongate socket, said walls having free lateral edge portions formed as flanges directed toward each other but spaced apart to provide a slot leading laterally into the socket, and a closure for the bottom of the socket, said closure comprising a part integrally united to the socket wall at one side of the slot and extending upwardly at the outer side of the socket wall at the other side of the slot, thereby to prevent the flanges from spreading apart.
25. A separable end stop for slide actuated fasteners of the kind in which opposed series of fastener elements are carried by flexible stringers and are moved into and out of engagement by a slider, said stop comprising a socket member and a pin member, the socket member having opposite side walls defining a vertically elongate socket, the edge portion of said walls being spaced to provide an elongate slot leading laterally into the socket, and a closure member for the bottom of the socket, said closure member being integrally united to one side wall and being turned up at its free extremity to overlap the outer surface of the other side wall, thereby to prevent abnormal spreading of the spaced edge portions of said wall, said closure member having an opening at the lower end of the socket, and the pin member having a tooth for engagement with said opening in the closure member.
30. A separable bottom stop for use in a slide actuated fastener of the kind in which a pair of stringers carries opposed series of interengageable fastener elements, and having a slider for moving said elements into and out of engagement, said end stop comprising independent members attached to the opposite stringers respectively, one of said members consisting of a piece of sheet metal bent to provide a socket having spaced walls provided with oppositely directed flanges, at their outer edges, respectively, the inner edges of said walls being integrally united by the fold of the material disposed between said walls to define a pocket for the reception of the beaded edge of the stringer, one of said walls having an integral extension constituting a bottom closure for the socket and the pocket, said bottom closure having an aperture therein, and the other of said stop members comprising a pin adapted to fit within the socket of the other member, said pin having a tooth at its lower end for engagement with the aperture in the bottom closure of the socket, the pin being curved longitudinally substantially from one end to the other to facilitate its passage through the slider into the socket.
35. A separable end stop for slide actuated fasteners, said stop comprising a socket member and a pin member, the socket member having substantially parallel front and rear walls defining a socket for the pin member, said walls being united by a fold thereby providing spaced jaws, each of double the thickness of the metal, for engagement with the stringer, said jaws having openings therethrough, an eyelet passing through the spaced jaws and the stringer, the opposite ends of said eyelet being headed over against the outer surfaces of the respective jaws thereby permanently to secure the socket member to the stringer, a garment member engaging the outer surface of one jaw and overlying the corresponding head of the eyelet, and a fastening member passing through the eyelet and garment member and uniting the stringer to said garment member.
40. An end stop device for slide actuated fasteners, said stop device comprising independent separable members each of said members consisting of a single piece of sheet metal bent to provide clamping jaws arranged to embrace the edge portion of one of the stringers respectively, the clamping jaws of each of said members having aligned openings therethrough, an attaching eyelet passing through the openings in the jaws of each member and through a portion of the corresponding stringer interposed between said

5 jaws, the opposite ends of said eyelet being headed over against the outer surfaces of the respective jaws thereby permanently to unite said member to the stringer, a flexible part engaging the outer surface of one jaw of each member and overlying the corresponding eyelet head, and a fastening member passing through the attaching eyelet of each of said stop members and the flexible part and uniting the stringer and corresponding stop member to said flexible part.

10 13. An end stop device for slide actuated fasteners of the kind in which opposed series of fastener elements are carried by flexible stringers, said stop device comprising a part mounted upon one of the stringers adjacent to the end of its series of fastener elements, an eyelet passing through said part and the stringer, said eyelet being headed over at each end, one head of the eyelet engaging an outer surface of said part, said eyelet securing said part to the stringer, another member overlying said outer surface of said part and the corresponding eyelet head, and an eyelet of smaller diameter passing through said first eyelet and through said other member and securing 25 said part and the stringer to said other member.

14. A blank for use in making the socket member of a separable end stop for fasteners of the class described, said blank consisting of a unitary piece of sheet material comprising the elongate portions 8 and 9 integrally joined to a central portion 10, the latter having an upwardly extending part 10^a, the outer extremities of the parts 8 and 9 being curved and integrally united by neck members 14 and 15 respectively to curved end portions of outer members 16 and 17 respectively, the part 16 having a notch 22 in its upper edge and an apertured tongue 23 projecting from its lower edge.

15. A blank as set forth in claim 14 in which the adjacent end portions of the parts 8 and 16 and of the parts 9 and 17 respectively are provided with openings 27.

16. In a multiple operated fastener installation adapted to be completely separated at both ends, a pair of stringers, opposed series of fastener members on said stringers, a slider movable on said stringers to engage and disengage said fastener members, separable end connections for said stringers comprising, in combination, a socket member on one stringer and a pin member on the other stringer for insertion into said socket member, said socket member having a portion adapted to attach said socket to one of said stringers at one edge thereof and spaced top and bottom plates extending across the opposed stringer from said portion and receiving the pin, and an end plate integral with one of said plates and at the lower end thereof and bent toward the opposed plate thereby to close the end of said socket member, said end plate having an aperture therethrough and receiving a portion of the pin member to prevent separation of said socket and said pin member by transverse stresses exerted on the stringers.

17. A separable end connection of the class de-

scribed comprising, in combination, a pin member and a box-like socket member, said box-like socket member formed from a single piece of sheet metal having an attaching portion and top and bottom plates extending outwardly from said portion and thereafter inwardly toward each other to form a tubular pin-receiving portion and an end plate formed integral with one of said plates and bent against the opposed plate thereby to close the lower end of said socket, said end 10 plate having an aperture therethrough and said pin member being adapted to be inserted within said socket member between said plates and having its end passing into the aperture in said end plate to retain said pin member within said socket member and to prevent accidental separation of said pin and socket by lateral stresses.

18. A separable end connection of the class described comprising, in combination, a pin member and a box-like socket member, said box-like 20 socket member formed from a single piece of sheet metal having an attaching portion and top and bottom plates extending outwardly from said portion and thereafter inwardly toward each other and an end plate formed integral with one of 25 said plates and bent against the opposed plate thereby to close the lower end of said socket, said end plate having an aperture therethrough and said pin having a projection of less cross-sectional area than the pin member proper and passing 30 into said aperture for the purposes described.

19. In a multiple operated fastener installation adapted to be completely separated at both ends, a pair of stringers, opposed series of fastener members on said stringers, a slider movable on 35 said stringers to engage and disengage said fastener members, separable end connections for said stringers comprising, in combination, a box-like socket member on one stringer and a narrow pin-like member on the other stringer for insertion 40 into said socket member, said pin member being formed from a single piece of sheet metal having a plurality of projections at the inner face and a portion offset from the lower end of said pin member, said projections adapted to wedge 45 a stringer against the opposed inner face of said member to affix said member to said stringer, said box-like socket member being formed from a single blank of sheet metal and having a folded-in attaching portion at one side thereof and 50 spaced top and bottom plates extending from said portion toward the opposed stringer a distance approximately the combined width of two fastener elements and thereafter inwardly toward each other and an end plate formed integral with 55 one of said plates and bent against the opposed plate thereby to close the lower end of said socket, said end plate having an aperture therethrough and adapted to receive the said offset portion of said pin member thereby to retain said pin 60 member within said socket member and to prevent accidental separation of said end connecting members when stresses are exerted thereon.

ROBERT C. LEGAT. 65
